Inventor,
Joseph Gioiosa.

By *Charles S. Gooding, Atty.*

UNITED STATES PATENT OFFICE

JOSEPH GIOIOSA, OF MILTON, MASSACHUSETTS

FIREWORKS

Application filed September 9, 1930. Serial No. 480,658.

This invention relates to an improvement in fireworks and particularly to a means whereby firework display units may be clamped to a frame and firmly held thereon 5 while being discharged.

The invention consists in the combination and arrangement of parts set forth in the following specification and particularly as pointed out in the claim thereof.

10 Referring to the drawings:—

Fig. 1 is a front elevation of a firework embodying my invention.

Fig. 2 is an enlarged detail sectional elevation taken on the line 2—2 of Fig. 1.

15 Like numerals refer to like parts throughout the several views of the drawings.

In the drawings, 5 is a rotary frame of a type commonly employed in the manufacture of "set piece" types of fireworks, the frame 20 illustrated being constructed in the form of a wheel. Fastened to the periphery of the rotary frame 5 are a plurality of U-shaped clamps 6, each clamp comprising two arms 7 having prongs 8 projecting inwardly therefrom. Each clamp 6 is firmly secured to the frame 5 by means of a rivet 9 which extends through the clamp and frame and is riveted thereto in a well-known manner. The rivet 9 holds the clamp 6 to the frame 5 with sufficient friction to hold said clamp firmly in position, nevertheless it is evident that the clamp may be rotated upon the rivet against the action of the friction if it is so desired.

Although the drawing illustrates the 35 clamps 6 as being secured to the outer periphery of the rotary frame 5, it is evident that these clamps may be secured to the sides of said frame without departing from the spirit of the invention.

40 In using the device a firework display unit 10, which, for example, may be a unit emitting a colored flame, is inserted between the arms 7 of the clamp 6 and pushed inwardly therebetween until it is engaged by the prongs 8. The arms 7 are made of spring metal so

45 that they will yield sufficiently to allow the firework unit to be inserted therebetween, but will firmly hold said unit in position after it is inserted.

50 The various units 10 are connected together

in a well-known manner by sections of fuse 11 and one of said units is lighted by igniting a fuse 12 which hangs loosely therefrom.

It is evident that many different effects 55 may be obtained by changing the positions of the various clamps 6 upon the frame 5, this change of position being accomplished by rotating the clamps upon their respective rivets.

I claim:

A firework having, in combination, a frame, 60 a clamp fast thereto and embodying a pair of oppositely disposed spring arms adapted to clamp a firework display unit therebetween, and a prong projecting from one of said arms 65 toward the other.

In testimony whereof I have hereunto set my hand.

JOSEPH GIOIOSA.
